LOCKING DEVICE

John J. Hays, Whitestone, N. Y., assignor to
Sentry Lock Company, Inc., Flushing, N. Y., a
corporation of New York

Application September 12, 1933, Serial No. 689,145

20 Claims. (Cl. 70—54)

An object of the invention is to provide a locking device which may be used for various purposes, although it is of particular value as a means for locking automotive vehicles.

Another object of the invention is to provide a locking device having a plurality of keys, one or more of the keys serving to open or unlock the device, certain other of the keys serving to block and prevent the unlocking of the device, and another key or keys serving to restore the parts for operation by the first mentioned key or keys.

Still another object of the invention is to provide the locking device with means to lock a steering post, means to open and close a switch, and means to lock a casing in which the locking device is disposed.

A further object of the invention is to provide the locking device with a rocking member having a blocking arm, a restoring arm and an operating arm, with means to operatively engage the arms, so that the said means may engage the restoring arm to move the rocking member to a position where the operating arm may be engaged by the said means, the said means also serving to engage the blocking arm to move the rocking member to position the operating arm out of position for engagement with the said means.

The invention also comprehends means to unlock the steering post and to close a switch which is held in operative position after it has been moved thereto.

Additional objects of the invention will appear in the following specification in which the preferred form of the invention is described.

In the drawings similar reference characters refer to similar parts in all the views, of which

Figure 1 is a fragmentary view showing the locking device mounted on the steering post of an automobile,

Figure 2 is a sectional view on the line 2—2 of Figure 1,

Figure 3 is an inverted plan view of the cover of the casing shown in Figures 1 and 2 of the drawings,

Figure 4 is an enlarged sectional plan view of the casing with the cover removed,

Figure 5 is a sectional view on the line 5—5 of Figure 4,

Figure 6 is a sectional view similar to the sectional view illustrated in Figure 5, but showing the rocking members in blocking position,

Figure 7 is a sectional view on the line 7—7 of Figure 4,

Figure 8 is an enlarged sectional view on the line 8—8 of Figure 4,

Figure 9 is a side elevation of one of the keys with its lateral extension,

Figure 10 is a plan view of Figure 9, and

Figure 11 is an enlarged view of one of the screws for holding the cover of the casing in place.

By referring to the drawings, it will be seen that a casing 15 is provided, which, as shown in Figures 1, 2 and 7, is normally secured to a steering post 16 of an automotive vehicle, but it will be understood that the casing 15 may be mounted in any desired manner for use not only in connection with a steering post, but also in connection with any other article or device which is to be locked. The casing 15 has a cover 16, the cover 16 having lugs 17 with apertures 18, the said apertures 18 registering, when the cover 16 is closed, with threaded apertures 19 in the sides of the casing 15. Disposed in the apertures 18 and 19 at each side of the casing 15 there is a screw 20, which is best shown in Figure 11, each screw 20 having a thread 21 which is spaced from a thread 22 on the screw 20, the second thread 22 serving as a head. It will be understood that these screws 20 may be turned home in the threaded apertures 19 and in the apertures 18, when they will be disposed as illustrated in Figures 4, 5 and 6 of the drawings.

Journaled in bearings 23 and 24 in the casing

15 there is an operating or service member 25, the operating member 25 having arms 26 and 26' which are adapted to engage the screws 20 be-

tween the threads 21 and 22, as shown in Figures

5 and 6 to prevent the withdrawal of the screws

20 from the apertures 18 and 19. The inner end

of the operating member 25 has an opening 27 in

which there is a spring 28, the spring 28 serving

to press the operating member 25 to the left

and to the position shown by the dotted lines in

Figure 4, when the operating member is free.

When the operating member 25 is rotated and is

moved to the left, as shown by the dotted lines in

Figure 4, the arm 26' will be disposed in a groove

29 at the inner side of the casing 15, the spring

28 serving to hold the operating member 25 to

the left with its said arm 26' in the said groove 29.

Disposed in the casing 15 there are two car-

riages 30 which are spaced apart, as best shown

in Figures 5 and 6. Extending from a plate 31

secured to the bottom of the casing 15 there are

guide pins 32 which extend through apertures

33 in the carriages 30. There is also another guide

pin 34 which is secured to the plate 31, this guide

pin 34 extending in a guideway 35 in the carriage

30, the head of this carriage at 36 closing the guideway 35 to limit the downward movement of the carriage relatively to the plate 31. There is a channel 37 around the guideway 35 in which a spring 38 is disposed, the spring 38 serving to hold the carriage yieldingly upwardly and away from the plate 31. Each of the two carriages 30 is constructed and mounted in the manner described and each carriage 30 has upwardly extending arms 39 in which a shaft 40 is journaled, the shaft 40 at one end being disposed in a slot 41 in the casing 15 and the other end 42 of each of the shafts 40 being normally disposed in a slot 43 in the operating member 25.

15 Mounted on each of the shafts 40 there is a plurality of blocking arms, which are indicated in the drawings by the reference characters 44^a, 44^b, 44^c, 44^d, 44^e, 44^f, 44^g and 44^h. As will best be seen by referring to Figure 4 of the drawings, these blocking arms 44^a, 44^b, 44^c, 44^d, 44^e, 44^f, 44^g and 44^h extend in one direction. Each of the shafts 40 also has a restoring arm 45 which extends in an opposite direction and each of the shafts 40 has an operating arm 46 which normally extends upwardly, as shown in Figure 5. When the shafts are in normal position with the blocking arms, the restoring arms and the operating arms disposed as shown in Figures 4 and 5, the blocking arms 44^a, 44^b, 44^c, 44^d, 44^e, 44^f, 44^g and 44^h will be inclined slightly upwardly and the restoring arms 45 will be inclined slightly downwardly, as best shown at the left in Figure 5. The blocking arms, the restoring arms and the operating arms are interchangeable and are secured to the shafts 40 by means of clamping members 47 which are secured together by screws 48.

20 The cover 16 is shown with four rows of keys 49, 50, 51 and 52, each of the keys having a lateral extension 53. As best shown in Figure 3, the lateral extensions 53 on the keys 52 lap the lateral extensions 53 on the keys 51 and the lateral extensions 53 on the keys 50 lap the lateral extensions on the keys 49. By referring to Figures 2 and 4 of the drawings, it will be seen that the key G in the row 51 will have its lateral extension 53 disposed at the arm 44^e, that the lateral extension 53 on the key J will have its extension disposed at the arm 44^f, that the lateral extension 53 on the key K in the row 52 will have its lateral extension at the arm 44^g, that the lateral extension 53 on the key H in the row 51 will have its lateral extension at the arm 46, that the lateral extension 53 on the key L in the row 52 will be disposed at the arm 44^h, and that the lateral extension 53 on the key I in the row 51 will be disposed for engaging the arm 45. In a similar way, the lateral extension 53 on the key C will be disposed for engaging the arm 44^d, the lateral extension 53 on the key F will be disposed for engaging the arm 44^e, the lateral extension 53 on the key B will be disposed for engaging the arm 45, the lateral extension 53 on the key E will be disposed for engaging the arm 44^b, the lateral extension 53 on the key A will be disposed for engaging the arm 46, and the lateral extension 53 on the key D will be disposed for engaging the arm 44^a. The arms 44^a, 44^b, 44^c, 44^d, 44^e, 44^f, 44^g and 44^h are blocking arms and when they are pushed downwardly by the lateral extensions 53 on their companion keys, this action will serve to rotate the shafts 40 to position the shafts with their several arms as shown in Figure 6. When in this position, the operating arms 46 will be disposed at recesses 54 in the lateral extensions 53, of the keys A and H

respectively; so that, when the shafts are so positioned, the arms 46 will not be engaged by the lateral extensions 53 on the associated keys and that there will be no downward movement of the carriage 30 in such a case.

80 Therefore, to operate the device, it is necessary to press downwardly the keys B and I having the lateral extensions 53 at the restoring arms 45, which will serve to rotate the shafts 40 to position the arms as shown in Figure 5 of the drawings. When this has been done, the keys A and H having lateral extensions 53 disposed at the arms 46 may be pressed downwardly in contact with said arms 46, which will press down the carriages 30 against the resiliency of the springs 36, which will move the ends 42 of the shafts 40 downwardly and out of the slots 43 in the operating member 25, this being shown by the dotted lines in Figure 8 of the drawings.

90 As shown in Figures 3 and 5, the keys are disposed for moving in apertures 55 in the cover 16, the cover having at its underside guide members 56 in which are disposed guide pins 57, springs 58 being provided for holding the keys yieldingly upwardly.

95 As has been stated, when the keys B and I operating the restoring arms 45 have been operated, and the keys A and H operating the operating arms 46 are subsequently operated, the carriage 30 is moved downward to move the ends 42 of the shaft 40 out of the recesses 43, as has been stated. The operating member 25 may then be rotated by means of its fingerpiece 59, which will move the arm 26' in alignment with the groove 29 in the casing 15. The spring 28 will then serve 100 to move the operating member 25 outwardly to the position shown by the dotted lines in Figure 4, which will dispose the arm 26' in the said groove 29, which will prevent a further rotary movement of the operating member 25 until the 105 operating member 25 is again moved inwardly. With the operating member 25 disposed outwardly, and with its arm 26' disposed in the groove 29, the slots 43 in the operating member 25 will be disposed away from the ends 42 of the 110 shafts 40, so that the carriages 30 will be held downwardly, although the keys, after their operation, will return to their normal positions by means of the springs 58.

115 With the rotary movement of the operating member 25, an arm 60 on the operating member 25 will be moved against a switch member 61 to press the said switch member 61 against a switch member 62 to close a circuit which may be connected with the ignition system and, if desired, with the starter of an automotive vehicle. The operating member 25 also has an arm 63 which, when the operating member 25 has been rotated as has been described, will press downwardly against an arm 64 having a dog 65 which normally engages ratchet teeth 66 on a collar 67 secured to the steering shaft 68 in the steering post 16'. It will, therefore, be seen that, when the proper keys are pressed downwardly to engage the restoring arms 45 to position the arms 46 upwardly and, when the keys, which serve to operate the said operating arms 46, are pressed downwardly, the operating member 25 will be free from the ends 42 of the shafts 40 and that, with the rotation of the operating member 25, the switch having the switch members 61 and 62 will be closed and that the dog 65 will be moved out of engagement with the ratchet teeth 66 on the collar 67 secured to the steering shaft 68 and, further, that the arm 26' on the operating 120

member 25 will be moved into alignment with the groove 29. With the operating member 25 so disposed, the spring 28 will press the operating member 25 outwardly to position the arm 26' in the groove 29 with the switch closed and the dog 65 free from the ratchet teeth. The automotive vehicle may then be operated in the usual manner.

When the operating member 25 is disposed as shown in Figures 5, 6 and 7 of the drawings, the arms 26 and 26' on the operating member 25 will be disposed in engagement with the threaded sleeves 22 on the screws 20, which will serve to lock the cover 16 on the casing 15, as well as to lock the steering shaft 68 and, with the arm 60 disposed away from the switch member 21 so that the switch will be open. It will, therefore, be understood that it will be impossible to remove the cover 16 from the casing 15 without knowing the combination of the locking device. However, when the combination of the locking device is known and when the locking device is opened, the cover 16 may be readily removed from the casing 15 to permit of a readjustment of the arms 44, 45 and 46 on the shafts 40.

It will be understood that, with the ratchet teeth 66, when the device is in locked position, it will nevertheless be possible to turn the steering wheel to permit the automotive vehicle to advance to the left, so that it may be moved away from the curb when occasion requires.

What is claimed is:

1. A locking device having a rocking member with operating means, blocking means and restoring means, a manipulatable member for engaging the operating means when the rocking member is in a predetermined position relatively to the said second member, manipulatable members for engaging the blocking means to rotate the rocking member away from the said position, and a manipulatable member for engaging the restoring means for rotating the rocking member to the said predetermined position.

2. A locking device having a movable member with operating means, blocking means and restoring means, manipulatable members for engaging the operating means when the movable member is in a predetermined position relatively to the said members, manipulatable members for engaging the blocking means to move the movable member away from the said position, and manipulatable members for engaging the restoring means for moving the movable member back to the said position.

3. A locking device having a rocking member with operating means, blocking means and restoring means, a manipulatable member for engaging the operating means when the rocking member is in a predetermined position relatively to the said member, manipulatable members for engaging the blocking means to rotate the rocking member in one direction away from the said position, and manipulatable members for engaging the restoring means for rotating the rocking member in the opposite direction to the said predetermined position.

4. In a locking device, a rocking member having blocking arms and a restoring arm, the rocking member also having an operating arm, a member for operatively engaging the operating arm when the rocking member is rotated to a predetermined position, members for engaging the blocking arms for rotating the rocking member away from the said position, a member for engaging the restoring arm for rotating the rock-

ing member to the said predetermined position, and operative means operable by the rocking member.

5. In a locking device, a rocking member having blocking arms extending in one direction and a restoring arm extending in another direction, the rocking member also having an operating arm extending in a direction between the blocking arms and the restoring arm, a member for operatively engaging the operating arm when the rocking member is rotated to a predetermined position, members for engaging the blocking arms for rotating the rocking member away from the said position, a member for engaging the restoring arm for rotating the rocking member to the said predetermined position, and operative means operable by the rocking member.

6. In a locking device, a rocking member having blocking arms extending in one direction and a restoring arm extending in another direction, the rocking member also having an operating arm extending in a direction between the blocking arms and the restoring arm, a member for operatively engaging the operating arm when the rocking member is rotated to a predetermined position, members for engaging the blocking arms for rotating the rocking member away from the said position, the second mentioned member having a recess for receiving the operating arm when the rocking member is rotated away from the said position by the third mentioned members, a member for engaging the restoring arm for rotating the rocking member back to the said predetermined position, and operative means operable by the rocking member.

7. In a locking device, a shaft, blocking arms extending in one direction from the shaft and a restoring arm extending in another direction from the shaft, an operating arm extending in a direction from the shaft between the blocking arms and the restoring arm, the blocking arms, the restoring arm and the operating arm being interchangeable on the shaft, means for securing the said arms to the shaft, members for engaging the arms respectively, the members having recesses positioned for receiving the operating arm when the shaft has been rotated by the engagement of one of the members with the blocking arms, and operative means operable by the shaft.

8. In a locking device, a shaft, blocking arms extending from the shaft in one direction, a restoring arm extending from the shaft in the opposite direction, an operating arm extending in a direction from the shaft between the blocking arms and the restoring arm, the arms being interchangeable, means for securing the arms to the shaft, members positioned for operatively engaging the arms, the members having recesses for receiving the operating arm when the shaft has been rotated by the engagement of one of the blocking arms by one of the members, and operative means operable by the shaft.

9. In a locking device, a shaft, blocking arms extending from the shaft in one direction, a restoring arm extending from the shaft in another direction, an operating arm extending from the shaft in a direction between the blocking arms and the restoring arm, keys having lateral extensions for operatively engaging the arms, there being a recess in each of the lateral extensions for receiving the operating arm when the shaft has been rotated by the engagement of a lateral extension with one of the blocking arms, and operative means operable by the shaft.

10. In a locking device, a shaft, blocking arms extending from the shaft in one direction, a restoring arm extending from the shaft in another direction, an operating arm extending from the shaft in a direction between the blocking arms and the restoring arm, two rows of keys spaced apart at the sides of the arms, the keys having lateral lapping extensions disposed for operatively engaging the arms, there being a recess in each of the lateral extensions for receiving the operating arm when the shaft has been rotated by the engagement of a lateral extension with one of the blocking arms, and operative means operable by the shaft. 80
15. In a locking device, a carriage having a shaft, resilient means for holding the carriage yieldingly in a predetermined position, blocking arms extending from the shaft in one direction, a restoring arm extending from the shaft in another direction, an operating arm extending from the shaft in a direction between the blocking arms and the restoring arm, means for securing the arms to the shaft, members positioned for operatively engaging the arms, each of the members having a recess for receiving the operating arm when the shaft has been rotated by the engagement of one of the blocking arms by one of the members, and operative means operable by the carriage. 85
20. 12. In a locking device, an operating member, a shaft having means for locking the operating member, blocking arms extending from the shaft in one direction, a restoring arm extending from the shaft in another direction, an operating arm extending from the shaft in a direction between the blocking arm or arms and the restoring arm, members for engaging the blocking arms for rotating the shaft in one direction, a member for engaging the restoring arm for rotating the shaft in the opposite direction, and another member for engaging the operating arm for moving the shaft relatively to the operating member when the shaft has been rotated by the engagement of the second mentioned member with the restoring arm. 90
25. 13. In a locking device, an operating member, a shaft having means for locking the operating member, operating means, restoring means and blocking means on the shaft, members for engaging the blocking means for rotating the shaft in one direction, a member for engaging the restoring means for rotating the shaft in the opposite direction, and another member for engaging the operating means for moving the shaft relatively to the operating member when the shaft has been rotated by the engagement of the third mentioned member with the restoring means. 95
30. 14. In a locking device, a casing having a cover, a lug on the cover with an aperture, there being an aperture in the casing which registers with the first mentioned aperture when the cover is closed, a member disposed in the apertures to secure the cover, the member having a head on its inner end, a rotatable operating member in the casing, and an arm on the operating member for engaging the head to hold the first mentioned member in the apertures. 100
35. 15. In a locking device, a casing, an operating member rotatably disposed in the casing, the operating member having a slot in one of its sides, locking mechanism having a member nor- 105
40. mally disposed in the slot to prevent the rotation of the operating member, a control element, locking means for the control element, and means on the operating member for moving the locking means relatively to the control element. 110
45. 16. In a locking device, a casing, an operating member rotatably disposed in the casing, the operating member having a slot in one of its sides, locking mechanism having a member normally disposed in the slot to prevent the rotation of the operating member, a rotatable element having ratchet teeth, a spring-pressed dog for engaging the ratchet teeth, and means on the operating member for moving the dog away from the ratchet teeth. 115
50. 17. In a locking device, a casing, an operating member disposed for rotating and for moving longitudinally in the casing, the operating member having a slot in one of its sides, locking mechanism having a member normally disposed in the slot to prevent the rotation and longitudinal movement of the operating member, a rotatable element, locking means for said element, and means on the operating member for moving the locking means relatively to said element. 120
55. 18. In a locking device, a casing having a cover, a lug on the cover with an aperture, there being an aperture in the casing which registers with the first mentioned aperture when the cover is closed, there being a groove in the inner wall of the casing adjacent the second mentioned aperture, an operating member disposed for rotating and for moving longitudinally in the casing, the operating member having a slot in one of its sides, locking mechanism having a member normally disposed in the slot to prevent the rotation and longitudinal movement of the operating member, a rotatable element, locking means for said element, means on the operating member for moving the locking means relatively to said element, a member normally disposed in the apertures and having a head adjacent its inner end, and an arm on the operating member normally engaging the head, the arm being disposed in the groove to prevent the rotation of the operating member when the operating member is rotated and is moved longitudinally. 125
60. 19. A lock including a carrier having a relatively movable locking member, resilient means to retain the carrier in a normal position so that the locking member may engage a part to be locked, a plurality of spring actuated keys, and a plurality of projections on said locking member with which said keys are adapted to cooperate to move the locking member relatively to the carrier, and then move both the carrier and the locking member, subject to the action of the resilient means, to unlock said part. 130
65. 20. A lock including a carrier having guided up and down movement, a locking member mounted on said carrier for turning movement with respect thereto, resilient means to retain the carrier up in a position so that the locking member may engage a part to be locked, a plurality of manipulatable spring pressed keys, means on said locking member with which said keys are adapted to severally cooperate to turn the locking member relatively to the carrier, and then move both the carrier and locking member downwardly, subject to the action of the resilient means, to unlock said part. 135
